BRICKLAYER'S LINE HOLDER

Ralph C. Surratt, 5037 W. 38th Ave., Denver, Colo.

Filed Feb. 5, 1962, Ser. No. 68,689

Term of patent 7 years

(Cl. D51—1)

FIG. 4.

FIG. 1.

FIG. 2.

FIG. 3.

FIG. 5.

I claim:

The ornamental design for a bricklayer's line holder as shown.
